FISHING LURE

William D. Storm, 1031 Canterbury,
Norman, Okla. 73069

Filed Nov. 26, 1965, Ser. No. 88,236

Term of patent 14 years

(Cl. D31—4)

FIG. 1

FIG. 2

FIG. 3

FIG. 4

FIG. 5

FIGURE 1 is a side elevation view of a fishing lure showing my new design, the broken line showing of the hooks is for illustrative purposes only.

FIGURE 2 is a top plan view of the fishing lure depicted in FIGURE 1;

FIGURE 3 is a bottom plan view of the fishing lure depicted in FIGURE 1;

FIGURE 4 is a front elevation view of the fishing lure depicted in FIGURE 1; and

FIGURE 5 is a rear elevation view of the fishing lure depicted in FIGURE 1.

I claim:

The ornamental design for a fishing lure, as shown and described.
